UNITED STATES PATENT OFFICE.

JASPER P. WARNER, OF DOWAGIAC, MICHIGAN.

GRIPES FOR SPRING HARROW AND CULTIVATOR TEETH.

SPECIFICATION forming part of Letters Patent No. 233,718, dated October 26, 1880.

Application filed August 4, 1880. (Model.)

To all whom it may concern:

Be it known that I, JASPER P. WARNER, of the city of Dowagiac, county of Cass, and State of Michigan, have invented a certain Improvement in Grips for Holding and Adjusting the Spring-Teeth of Harrows and Cultivators, of which the following is a specification.

The object of my invention is to furnish a grip for spring harrow and cultivator teeth by their edges, where a more permanent fastening can be had than fastening at their sides, where there is constant springing, which causes the teeth to work loose; also, by fastening teeth at their edges they can be placed wholly upon the inside of a harrow-frame, leaving the outside surface smooth and not liable to catch on snags, roots, stones, or growing grain while being drawn forward.

By the use of my grip the teeth can readily be changed from a hooking or digging tendency to a dragging or scraping one. The grip admits also of setting the teeth up or down to gage the depth of work or to increase or decrease the spring of the teeth, as is often required.

By the use of my invention the teeth are firmly held in any desired position without drilling or punching holes through them, as is now done, requiring extra labor, and weakening the spring-teeth where the most strength is needed. By the use of this grip the spring-teeth may be sharpened at both ends, and the ends may be swaged of different widths, as I do not fasten at their ends but below them.

To enable others skilled in the art to which my invention belongs to make and use it, I will proceed to describe its construction and operations.

In the five drawings forming a part of the specification, Figure 1 is a top view of the device embodying my invention. Fig. 2 is a side-elevation, with the tooth B and cap D shown in a changed position, as shown by the dotted lines. Fig. 3 is a horizontal sectional view on the line $x-x$ in Fig. 2. Fig. 4 is a face view of the shoulder-iron E upon a section of the harrow-frame A. Fig. 5 is a face view of the inner end of the central section, C, showing its row of cast ridges c c.

The harrow-gripe consists of three metal sections, as best shown in the drawings, Fig. 3,

consisting of the parts E, C, and D, respectively. The section E is called the "shoulder-iron," as it is provided with a long bearing upon the harrow-frame A back of the bolt-hole cast in it, through which the bolt F passes and holds it to the harrow-frame. The shoulder-iron is provided with a hub, K, about two and a half inches across, and is twice as thick upon its back side as it is in front, which causes the tooth, in this instance, to stand on an angle of about thirty degrees to that of the sides of the harrow-frame. Changing the thickness of the back portion of the hub K will change the angle of the tooth.

The shoulder-iron is provided with a flange, l, around the periphery of the hub K, which projects beyond the end of the hub one-fourth of an inch. Within the flange l and around the hub is a row of cast ridges, e' e', running from the flange toward the center of the hub about half-way.

The upper and lower edges of the shoulder-iron are provided with cast projections T, that just fit over the edge of the top and bottom of the harrow-frame A, which prevents it from turning on the wood-work. A portion of the hub of the shoulder-iron is cut away in front, forming the front side about one-half inch in front of the bolt-hole cast in it. The portion of the shoulder-iron back of the hub is about one-fourth of an inch thick.

The central section, C, at its inner end, is of the same form as the exterior of the hub on the shoulder-iron, but being enough smaller so that its inner end will just pass within the flange on the shoulder-iron, which helps to hold it in position. The central iron is circular upon the back side, but, like the hub K, has a portion of the circle cut away just in front of the hole cast in it to receive the bolt F. The inner end of the central section is provided with a row of cast ridges, c c, same as described upon the hub K, which are intended to fill the spaces of each other when the two sections are forced together, which will form a lock and prevent the central section from turning around. The end of the central section just in front of the bolt-hole and upon the outside is provided with a rib, L, about one-fourth of an inch deep and about the same width, running the length of the front side, forming a

portion of the front side and acting as a jaw, passing over the front edge of the spring-tooth B. The back portion of the central section is concave, extending from the inner end outward 5 (in this instance) one and three-eighths inch, designed to be long enough for a spring-tooth one and a half inch wide. The length of the concave portion O of the central section will always depend upon the width of tooth used, 10 and should always be about one-eighth of an inch shorter than the teeth are wide. The concave portion of the central section extends around its inner end until the upper and lower shoulders stand in line just in front of the 15 bolt-hole through its end, and just back of the rib L far enough to form a groove wide enough to receive the edge of the spring-tooth B. The concave portion O of the central section is about one-fourth of an inch in thickness, and 20 its edges are square. The distance through the concave is about two inches.

The section D is called the "gripping-cap." It is about one-half inch thick, and consists of 25 two-thirds of a circle having a portion cut away upon its front edge, leaving it smooth, and upon the inside, along the front edge, is a cast rib, S, of the same proportions as the one described upon the central section, C, and is designed to fit over the front edge of the spring- 30 tooth B, just opposite the rib L on the central section. The back portion of the gripping-cap is circular, and around its periphery, projecting from the inner side, is a flange, d, of the same proportions as the one described upon 35 the shoulder-iron E, but having a portion cut out to form a groove wide enough to admit the edge of the spring-tooth B between the shoulders and the rib S.

The gripping-cap is designed to fit over and 40 onto the end of the concave portion of the central section, and is made enough larger so the concave portion will just pass within the flange d of the cap. Just back of the rib S is a hole near the center of the cap through which the 45 bolt F passes. The face of the cap is flat, having its edge slightly beveled.

To use the gripe the shoulder-iron E is placed upon the side of the harrow-frame A, having a hole bored through it about three-eighths of 50 an inch across. The bolt F is inserted through the frame and the shoulder-iron. The central section, C, is then slipped upon the bolt with its end of cast ridges fitting into the spaces

of the shoulder-iron. The cap D is then slipped upon the bolt with its flange d fitting 55 around the concave portion of the central section. The nut is then placed upon the bolt. The spring-tooth B is inserted with its edges in the grooves of the central section and gripping-cap. The nut is turned up, drawing the cap up to the central section, drawing the central section, with its ridges, into the spaces of the shoulder-iron, and drawing the shoulder-iron firmly to the harrow-frame. Thus the bolt F not only holds the tooth in the gripe, 60 but holds the gripe together and to the harrow-frame, a very simple fastening. As the length of the concave of the central section is shorter than the tooth is wide, forcing the nut upon the cap causes the back portion of the 65 cap to rest upon the back edge of the concave, while the front portion, forming the rib or jaw, is constantly pressed upon the edge of the tooth, holding it firmly, as shown in Fig. 3; but by loosening the bolt F the bottom of the 70 tooth may be moved backward or forward, as shown in the drawings, Fig. 2. As the tooth is moved backward or forward the central section, C, and the cap D revolve around the bolt F, and by clamping the section C to the shoulder-iron E, forcing the ridges together will 75 hold the tooth firmly in its different positions.

The tooth may be raised or lowered in the gripe. By first loosening the nut and drawing up or pushing down on the tooth it will 80 slide through the gripe.

Having thus fully described my invention in the most exact terms that I can give, what I claim as new, and wish to secure by Letters Patent, is—

1. In a harrow-gripe, the shoulder-iron E, with its hub K, flange l, and ridges e' e'.
2. In a harrow-gripe, the central section, C, with its rib L, ridges e e, and concave extension O.
3. In a harrow-gripe, the gripping-cap D, with rib S and flange d.
4. In a harrow-gripe, the combination of the shoulder-iron E, central section, C, gripping-cap D, and bolt F, as and for the purposes shown and described.

JASPER P. WARNER.
